UNITED STATES PATENT OFFICE.

HERMANN F. CUNTZ, OF HARTFORD, CONNECTICUT.

VERTICAL BEACON.

Application filed August 16, 1922. Serial No. 582,171.

This invention relates to the night marking of airways or airlanes, and has for its object the novel projection of light beams to provide light spots or markers in space 5 specially adapted to meet the particular requirements of night flying. The invention involves the production of such night lights in the sky, and the methods of marking of air travel lanes, as well as apparatus for 10 effecting the same.

More particularly the invention involves the provision of a night light spot or spots which may be intermittent, and which may be provided as a progressive series of spots 15 at an approximately definite altitude in conjunction with variable light beams, and the production of such airplane illumination from apparatus carried by a moving vehicle, such as some part of a railroad train.

Particular forms of my invention are 20 based on the projection of beams skyward from a rail car, and controlling and varying the angle of the beam with due regard to the movement of the car, so that an approximate point reasonably within the altitude 25 lane which it might be desired to mark, will have a relative permanency for better visibility than laterally moving light beams. In this manner a ray projected may be moved 30 through an angle whereby it will have the appearance of pivoting about a point of three thousand feet altitude, so that while the major part of the beam would have a swift lateral movement, the persistency of the 35 focal point or point around which the beam swings would provide a greater certainty of permanency for visibility of air pilots, and would have periodic regularity from which relative motion of aircraft can be determined.

Thus a train may carry a searchlight 40 which would project a ray skyward at an angle, and the angle by direct projection or reflection would vary with the movement of the train, as, for example, in direct ratio to the speed of the train, thereby producing the effect of the beam pivoting about a focal point at a predetermined altitude depending upon the rate of change of angular projection. For some purposes two rays may be 45 projected from a train and in the plane of movement of the train, so that their intersection will more effectively mark a light spot under suitable atmospheric conditions, 50 at a predetermined altitude, but such double rays may also be angularly varied in syn-

chronism so that their intersection will approximately maintain a line or a flat arc of maximum luminosity or varied lines like fugitive writing at a predetermined altitude 60 above the train.

In particular, the practice of this invention will provide for the marking of airlanes by night, by the simple adoption of apparatus of not prohibitive cost or complexity, and carrying such apparatus on trains which have ample and usually surplus power readily available, and carry such skilled hands as may be required for attention and manipulation of the apparatus, so 70 that the route of a railroad may be quickly and economically equipped with all the power and apparatus and personnel necessary for effective and economical, and in other ways advantageous illumination of an 75 air route or airlanes between central points of air traffic.

For the purpose of more specific description of this invention, the accompanying drawings illustrate specific embodiments of 80 apparatus and illustrations of operation, which drawings forming a part hereof shown in:

Fig. 1 a side view of a railroad train with different positions of skyward beam pivoting about a predetermined altitude point.

Fig. 2 shows a side view of the front end of a locomotive illustrating the periodic skyward deflection of all or part of the headlight rays.

Fig. 3 shows the front portion of an electric locomotive with the apparatus for intermittent skyward projection of the headlight rays. Fig. 3^a shows in detail one form of intermittent and angularly varied skyward reflection of a searchlight ray. Fig. 3^b is a cross-section of the principal parts on line 3^b—3^b of Fig. 3.

Fig. 4 is a side view of a railroad train with dual skyward intersecting beams projected from an extended moving base. Fig. 4^a is a side view on a large scale of a searchlight and adjustable reflector and appurtenances on a train unit such as a locomotive tender.

Fig. 5 is a side view of a series of skyward swinging beams illustrated as projected from a moving train, with different positions of train shown to illustrate the method in operation.

Thus a locomotive 1 with a headlight 2 has an intermittently operated reflector 3

which may be given a position and angularity to suddenly project the beam A. The angle of the reflector 3 being varied with the position of the locomotive 1 maintains the 5 position of the beam directed substantially at a point B in space, and by the rate of change of the reflector 3 the pivotal point B may be predetermined, approximately, at an altitude of, say, one thousand, two thousand 10 or three thousand feet; or such altitude as the strengths of the ray and the predetermined conditions of airplane marking make desirable. When the headlight or searchlight has moved to the position 1^a, the beam 15 has assumed position C, and is then cut off so that as a headlight it projects horizontally on the tracks as indicated at D. Such operation may involve a short period of five seconds out of every minute, and the change 20 of angularity and the rate of change would be proportioned to the speed of the train, and preferably automatically governed by the speed of movement of the headlight or searchlight, or in any event the movement of 25 the reflector, whatever may be the original source of light. Thus with a high speed train the interruption of the headlight for skyward beam deflection might involve the period less than the distance of headlight 30 illumination when horizontal, so that in spite of a relatively short periodic upward deflection, there would be no portion of the track that had not been illuminated by the headlight.

35 As shown in Fig. 2, the headlight in a usual position or in a lower position than has heretofore been the practice, would have the reflector apparatus supported rigidly in respect to the headlight with the necessary 40 mechanism to project the reflector in the path of the horizontal rays and to manipulate the movement of the reflector, as shown at 3. In this position the vertical or skyward rays could always be operated ahead 45 of the vertical and be allowed to pivot to a vertical position, without interference with existing locomotive parts, and without penetrating any steam or smoke or dust laden air. In Fig. 3 the headlight on an electric 50 locomotive would be projected by apparatus largely under cover of the hood of the locomotive and well positioned for protection, and for inspection, control or adjustment. In this position the vertical rays would be 55 above any line of vision of the engine driver and would, therefore, not interfere with his vision except for the relatively small time for skyward deflection intermittent with the long period of horizontal ray covering the track ahead.

60 As shown in Fig. 3^a, the reflector 3 is carried by a frame 4 with pins 5—5 on either side sliding in guide frame 6, pivoted at 7 to provide for varying angularity. This angularity in the form shown, is provided by

cams or wedges 8—8, the relative position of which determines the angularity of the guides 6, and the position of the wedges 8—8 in turn are determined by the rods 9—9 attached to levers 10—10 which are subject to control. The wedges 8—8 forcing the frame 6 in one direction are resisted by springs 11—11 constantly tending to force the guides 6—6 into a position of 45 degrees, in the case here illustrated. Thus the 70 wedges 8—8 are pulled into position shown in full-lines, by the levers 10—10 and due to stops 12—12 on said levers which are engaged by pins 5—5 when the reflector frame 4 is in retracted position drawn into such 75 inactive position by the action of a compressed air piston 13 acting on the lever 14 connected by a pivot 15 to the inner end of the reflector frame 4. A spring 16 fastened to one fixed point and at the other end engaging the end 17 of the lever 10, or engaging a single lever connected with a shaft to which both of the levers 10 are attached, tends to resist the engagement of pins 5—5, 80 but is suitably controlled by governor regulation subject to the speed of the vehicle. In this manner the housing of the reflector frame 4 pulls the levers 10—10 into a position dependent upon the vehicle speed, and by means of rods 9—9 determines the position of the cam or wedges 8—8, and therefore the initial angularity of the guides 6—6. When reflector frame 4 is projected 85 upwardly by the compressed air piston 13 90 acting on the lever, or levers 14, the reflector 3 immediately assumes the angularity determined by the position of the cams 8—8, but by the release of the pins 5—5 the levers 10—10 immediately begin to move under the action of the spring 16, turning the shaft 10^a 95 which through suitable gears, indicated at 10^b, the movement of the shaft is controlled by a governor, diagrammatically illustrated at 18, so that by suitable governor relations, the action of spring 16 will cause the respective interconnections to move the cams 8—8 progressively within the predetermined time desired to permit the guide frames 6—6 to be pivoted under the action of the 100 springs 11—11 about the pivot 7, into the 105 final position of 45 degrees. When the reflector 3 has thus been thrown into the position of intercepting the rays, and as moved through its predetermined angle, the compressed air piston automatically throws the 110 levers 14 and by quick action retrieves or houses the reflector 3 and its frame 4, thereby leaving the rays of the searchlight 2 115 unintercepted for their horizontal projection.

120 While for purposes of illustration a position of approximately 61 degrees initial angularity of reflector has been shown, with a progressive movement to a final position of 45 degrees, it will be understood that the 125 particular conditions for which the particu- 130

lar apparatus is intended, will determine the positions and angles to meet the desired skyward ray projection and the progressive movement and angular variation of the beam 5 in order to accomplish the purposes as hereinbefore and hereinafter described. Thus as illustrated, if it is assumed that the focal point B in Fig. 1 is intended to be at a 2000-foot lane above the source of the rays, then 10 from the initial position A of approximately sixty degrees to the position C forty-five degrees, the source of light would move approximately 1150 feet, that is the angular movement of the reflector should be steady 15 and at a rate of about one degree for each seventy-seven feet of movement of the source of light, and for this specific case the governor 18 would be set to permit lever 10 to move the wedge 8 so that for every seventy- 20 seven feet of movement of the source of light the reflector frame will have gradually changed half a degree so as to change the sky angle of rays one degree. The governor control is readily obtained by any suitable 25 connections as with the axles of a car or locomotive. Mechanism similar to speed indicators driven by a car axle, or any positive speed mechanism may be connected to shaft 10^a or elsewhere to move the rod 9 and 30 wedge 8 by any suitable mechanical means at a rate which would give an angular change to the ray of one degree for approximately seventy-seven feet of travel. Thus suitable 35 mechanism may be readily provided to deflect the reflector positively while the operator adjusts the rate of change until it corresponds with the speed at the time to maintain the focal point at the two thousand foot lane, or to adjust it for any other height of 40 lane in which it is desired to maintain the light spot. As shown in Fig. 4^a, a suitable 45 cowl or housing 20 provides for the elimination or minimizing of varying wind pressure against the reflector and reflector frame, as well as protection for the searchlight 2^a. Suitable current switching apparatus 21 may 50 be mounted as a part of the unit installation under the protection of the cowl so as to cut out the searchlight and produce the intermittent rays. As there shown, when the 55 searchlight 2^a is used only for skyward beam projection, if a periodicity, and not permanency of sky beams is desired the retrieving of the reflector 3 may be eliminated, and if a 60 fixed sky focus or pendulum spot is desired, the angular shifting of the reflector 3 is provided with intermittent quick return to its initial position and with a progressive change of angularity dependent upon the 65 vehicle speed, as, for example, in a similar manner to that described in connection with Fig. 3^a.

When two beams are used, as shown in Fig. 4, the angular positions of reflectors are 65 appropriately adjusted. Without change in

the angular positions of the reflectors a beam intersection at a predetermined altitude as E, produced by beams E' and E'' would provide an altitude airplane indication, but as shown by focus F and beams F' and F'' an initial position of cooperating beams is such that with movable reflectors synchronized to change their angularity in some proportion to the speed of the train, the focal spot may be substantially fixed or it may pass through 75 a flat arc at an approximate determined altitude, relative to the movement of the train, and after a predetermined fixity of position, a simultaneous angular shifting of the reflectors 3'' and 3''' will give the focal or 80 intersection point a new advance position and maintain the same with suitable regulation of reflector angularity, with a further intermittent shift or change so as to produce the effect of a series of more or less 85 fixed light spots with earthward radiating and moving rays focusing on said light spots, which in all cases will indicate the direction of movement of the source of light.

In Fig. 5 there is shown a train G with 90 vertical projecting apparatus H at the rear so that it is remote from the engine driver, so that the beam will have the least effect upon the engine driver's vision. This projecting apparatus H contains similar reflector apparatus with a source of beam such as a searchlight, adapted to project it as illustrated in the position of vertical ray J. The previous position of the train G' is to indicate the projection of the vertical ray beams by suitable mechanism, in the position of ray J', and while the train moves from G' to G the angularity changes from that of the beam J' to that of the beam J. The change of angularity being so timed with respect to the speed of the train, that it pivots substantially about a spot K, which of course will be variable due to the irregularity of speed and the jolting of the train, but the size of the beam at the focus K will be such that the mist or impurities in the air, moisture, etc., which would give a good searchlight ray luminosity at that point, would mean that such luminous spot would remain substantially fixed while the train passed from position G' to G, and would therefore make the focal point K a sky-light spot of sufficient duration and persistency, so as to afford more certain visibility than other parts of the ray, either above or below the focal point K, which would be moving quickly. The quick movement above and below the focal point K would cause the beams to move through denser or rarer zones or banks of moisture if such be present, and be therefore fluctuant light, thus relatively adding to the visibility of the focal spot K. The movement of the rays above or below the focal point would, however, present a distinctive sky mark, and the 100 105 110 115 120 125 130

4
direction of movement below the point K would indicate the movement of the source of light, and in that way would be informative to the night pilot and be an additional 5 guide besides the mere fact that the beacon emanated from a known route, and in addition to the information which the focal point would convey with respect to altitude.

10 The position G'' of the train and the position G''' it will be understood are preceding 75 positions in the movement of the train and are therefore shown in dotted lines, and would successively produce the sky beacon foci K'' and K' which would vanish as the 15 next succeeding position is established, but for purposes of illustration these are shown as if the step-by-step flashing was sufficiently frequent to provide some permanency of impression upon the retina thus indicating an altitude marking in the nature 20 of a light spot with a tail of dots or fainter spots of graduated distinctness. Furthermore, as here illustrated the reflector mechanism is so arranged that instead of shutting 25 off the light, the reflector is quickly shifted at intervals without intermission, which is illustrated by the light rays emanating from the source of light at the tail of the train in its successive positions.

30 In connection with modern train equipment, while locomotives are of sufficient current capacity for the purposes of vertical pendulum beacons as herein set forth, it is preferred to supply current as by a turbo- 35 generator as in a baggage car or on a tender, with suitable roof or hatch openings on such cars, or on a rear car as shown in Fig. 4. The entire reflector mechanism can be constructed to detachably mount on the 40 end of a car as shown in Fig. 5. It is quite reasonable to consider a special "lighthouse" car, namely, a car equipped with the usual, turbo-generator and a more powerful searchlight, and with radio and other apparatus, 45 and crew for the particular purpose of aiding night flying, in which case such a car would under suitable conditions serve the purpose of an aerial lighthouse moving over the route of night aerial travel, and a series 50 of cars would therefore serve the purpose of a large number of stationary lighthouses, and would have the advantage of self-contained power equipment, with ample power, with the entire equipment daily at a point 55 where overhauling or adjustment could be readily made, while each entire car lighthouse would involve possibly much less, and no more, in cost than a single fixed lighthouse with its adjuncts, crew and upkeep.

60 The movable lighthouse would have its inherent advantages of beam manipulation to provide focal points or relatively persistent light spots at predetermined altitudes, and detached spots or a contiguous series of 65 spots, or by suitable regulation of the change

of angularity of the reflector, the relatively persistent light spot might be moved in an arc or a line in the manner indicated in Fig. 4, and have various other modifications of sky beacon phenomena, and a great 70 variety of combinations and permutations of night beacons and also night signals may be provided.

In the commercial development special 75 cars with their equipment may include duplicate apparatus so as to produce combinations of fixed altitude spots and signals, or two altitude lines may be marked with light of relatively greater persistency or luminosity. The apparatus may be so mounted 80 as to be laterally shifted, and in such case duplicate apparatus tilted in opposite directions, namely, to either side of the path of the road, could be regulated to show in effect two parallel lines of light at a predetermined altitude. While the ordinary head-light for locomotives would suffice for reasonable visibility at 2000 feet altitude, and under suitable atmospheric conditions 85 three and four thousand feet, the current equipment now usual on ordinary electrically lighted railroad cars would be sufficient for stronger searchlights and much greater altitude markings, without requiring any special 90 development of equipment as far as current 95 is required.

A fixed lighthouse system means an expensive duplication at numerous points such as 15 to 20 miles apart, and would be used only intermittently on many routes before 100 the amount of traffic reached a point that would make such permanent installation efficient and warranted. Thus the car sky beacons would blaze the way for trans-continental night flying and serve the purpose, possibly better than permanent beacons, for many years before the installation of permanent beacons would be under any circumstances warranted.

105 It must also be noted that the reflector and searchlight equipment herein described as intended principally for railroad cars, can be mounted on motor cars preferably where long straight stretches of good highways would provide for reasonable regularity in the movement of the car, and to that extent highways, such as the Lincoln Highway, could be marked by motor car searchlights for night beacons, and with suitable regulation the night routes could 110 be blazed over different sections at different times of night when regular air traffic required, and it could also be momentarily started and blazed for any special night 115 emergency flight wherever the route desired 120 passes over long stretches of suitable highway.

125 While in certain forms of the night beacon it is contemplated that three to ten seconds vertical projection, then an interval for the 130

balance of a minute, would be a suitable night signal under certain conditions, a continuous advancing or jumping focal spot may in other cases be more suitable as a guide for the night pilot. With the various means of changing the nature of the signals, the altitude of marking, and then with the many variations in time and interval, it will be readily seen that a great many permutations and combinations are possible with this system of night beacons, so that any number of distinctive routes can be marked, thereby permitting a night flier to pick the different routes, or change from one to the other when within the range of visibility, having in each case practically a clear night map leading to any desired destination, and in addition an indication of direction, which would be based upon preknowledge of the operation of the railroad or high-way beacons on the different routes or at different times of night.

Many modifications may be made with respect to the method of projecting of vertical beacons containing the inventions hereinbefore described, and their method of use would be subject to innumerable modifications, without departing from the spirit of my invention.

What I claim and desire to secure by Letters Patent is:

1. A beacon for guiding aircraft at night, comprising a source of light beam, means for controlling the projection of said beam skyward and means for varying the angle a limited amount from the vertical, means for progressively varying said angularity of the beam synchronously with the speed of movement of the source of light along the ground, whereby ground motion of the source continuous in a substantially horizontal direction is accommodated with vertical angular change of the beam in a ratio to keep a point of the beam at a predetermined height above the source in a fixed position, for the purpose described.

2. In combination, a vehicle moving in a generally horizontal direction, a source of concentrated upward light beam carried by said vehicle, means for steadily and progressively varying the angularity of said beam from or to the vertical throughout a predetermined angle in a fixed ratio with the speed of the moving vehicle, and cooperating means for periodically setting the means of projecting the beam at the initial angle from which the progressive variation starts.

3. An aircraft beacon for guiding pilots at night by tracing a lane at a predetermined altitude above ground by relatively intensified light zones or spots, comprising a searchlight and reflector, means for controlling the skyward projection of a beam from the searchlight and means for automatically varying the angle of said beam gradually over a limited range from the vertical and

in a plane coincident with the direction of the lane, means for carrying such searchlight at a substantially uniform speed in the direction of the lane, and means for synchronizing the angle of skyward projection with the speed of movement of the searchlight over the ground, and means for periodically and uniformly shifting the spot of concentrated light step-by-step along the lane.

4. In combination with a moving vehicle, a search light, a reflector adapted at will to intercept forward rays of the search light and project them upward, means for steadily varying progressively the upward angle of the rays in the reverse direction from the movement of the vehicle and in a predetermined and angular ray coinciding with the rate of movement of the searchlight and the vehicle, and means for periodically and automatically changing the angle of the reflector to set the upward angle of projection of the rays at the initial position to repeat the steadily varying angular change.

5. A beacon for aircraft adapted to be established from a moving vehicle, comprising a train, a searchlight on said train, automatic means for varying the skyward angle of projection of a light beam on a focal point in the sky in the plane of movement of the moving vehicle, means for periodic variation of the focal point of skyward projection, and means for periodically interrupting said light beam.

6. In combination with a locomobile searchlight, a reflector, means for varying the angularity of the reflector for skyward projection of the beam, and means for intermittently shifting the reflector bodily in and out of the path of the light beam.

7. Means for projecting a light beam from a train comprising a source of concentrated beam, a movable reflector adapted to be periodically projected into the path of the beam, means for automatically varying the angularity of the reflector when intercepting the beam, and means for controlling said angularity in predetermined relation to the speed of the train.

8. Means for projecting a light beam from a train comprising a source of concentrated beam, a movable reflector adapted to be periodically projected into the path of the beam, means for automatically varying the angularity of the reflector when intercepting the beam, means for controlling said angularity in predetermined relation to the speed of the train, and means for automatically shifting the reflector in and out of the path of the beam at predetermined intervals.

9. A sky airplane lane indicating system comprising a concentrated light beam, a carrier therefor and means for moving the same parallel to the lane it is desired to indicate in the sky, means for gradually varying to a limited degree the angle of skyward projec-

- tion of the concentrated light beam synchronously with the movement of the source of the beam in the direction of the lane, such angular motion being in a direction whereby 45 a point in the light beam at a predetermined altitude will remain substantially stationary during a limited movement at the source of light, and means thereupon for automatically shifting the initial angle of projection to a 50 new advanced point of skyward projection and automatic resumption of the gradual angular change to produce again the appearance of a fixed altitude point or zone in the beam of intensified light.
- 15 10. A night beacon for navigation of aircraft, comprising means for tracing in the sky at a substantially fixed altitude an intensified or focal light spot or spots comprising two light beams intersecting at a focus, 55 sources of projection for said beams carried on movable supports moving synchronously and automatic means for synchronously shifting the angularity of said beams to maintain their focal intersection at substantially uniform altitude, but with intermittent fixed position and periodic shifting with relation to the source of movement of the lights. 60
- 20 11. A sky lighting system comprising sources of light for a plurality of beams intersecting at a substantially fixed sky focus at a predetermined altitude, a carrier for said sources of light movable along the surface of the earth, and automatic means for varying the angularity of the different beams synchronously. 65
- 25 12. A sky lighting system comprising sources of light for a plurality of skyward beams, means for varying the angularity of each of the beams in a predetermined manner whereby intersection of the beams will be maintained at a predetermined height above 70
- 30 the plane of movement of the source of light, and means for simultaneously varying the angularity whereby the focal point of intersection will be moved to follow a controller course in the sky. 75
- 35 13. A sky lighting system comprising sources of light for a plurality of beams, a reflector associated with each source of light adapted to produce a skyward deflection of the beams intersecting at a controlled or predetermined altitude, means for coordinating the movement of the reflectors whereby the intersection or focal point of the beams may be given any desired movement while constantly maintaining the intersection of the beams in the sky. 80
- 40 14. A system of sky lighting comprising moving sources of light emitting searchlight rays, and means for automatically varying the skyward angle of said rays synchronously with the motion of the sources of light to maintain their intersection at a point in space at a predetermined altitude and means for shifting the ray intersection, whereby a lane of intensified light spots or foci may be traced in the sky with greatly increased visibility directly over a desired route, such as a railroad or motor roadway. 85
- 45 15. A system of sky lighting comprising a plurality of sources emitting concentrated light rays, a source of power for each light source and a plurality of carriers each having a source of power, and means for varying the angular skyward projection of each ray, means for slow variation of the angular change of the ray at times and means for quick shifting of the angle of sky projection periodically. 90

This specification signed and witnessed this 12th day of August, 1922.

HERMANN F. CUNTZ.
